11 Claims. (Cl. 254—2)

This invention relates to hydraulic jacks, and has for an object the provision of a new and improved device of this character.

In the drawings accompanying this specification and forming a part of this application I have shown, for purposes of illustration, an embodiment which my invention may assume, and in these drawings:

Figure 1 is a broken top plan view of an embodiment of the invention.

Figure 2 is a broken side elevational view, partly in section, of the embodiment shown in Figure 1.

Figure 3 is an enlarged vertical sectional view, corresponding substantially to the line 3—3 of Figure 1.

Figure 4 is an enlarged vertical sectional view, corresponding substantially to the line 4—4 of Figure 1, showing parts thereof in one operative position.

Figure 5 is a vertical sectional view, corresponding substantially to the line 5—5 of Figure 4.

Figure 6 is a vertical sectional view, corresponding substantially to the line 6—6 of Figure 4.

Figure 7 is a vertical sectional view, corresponding substantially to the line 7—7 of Figure 3.

Figure 8 is an enlarged broken, elevational view, partly in section, corresponding substantially to the line 8—8 of Figure 1, while

Figure 9 is an enlarged fragmentary, vertical sectional view, of a valve arrangement employed in the invention.

The embodiment of the invention herein disclosed comprises a cast frame 10 of malleable metal, or the like, to permit slight weaving thereof, having identical side walls 11 and 12 projecting upwardly to a peak, as indicated at 13, one end 14 of the side walls 11 and 12 being integrally connected by a tie member 15, and short of the opposite end the walls 11 and 12 each merge into an elongated section 16 having an arcuate segment 17 provided with an inwardly extending flange 18 having holes 19 extending therethrough for a purpose hereinafter described, and the segments 17 terminate in a tie member 20 which integrally connects the side walls 11 and 12. Numerous other tie members 21 are provided which integrally join together the side walls 11 and 12, forming a skeleton frame cast integrally in one piece. An axle 22 extends through the side walls 11 and 12 at the end 14 of the frame 10, and is provided at its ends with wheels 23 rotatably secured to the axle 22 by nuts 24; and secured by screws 25 to the elongated section 16 of each

side wall 11 and 12 is a bracket 26 to which are mounted, in the usual manner, swivel wheels 27 providing means for moving the frame 10 to any desired direction.

Disposed between the side walls 11 and 12 of the frame 10 is a jack unit 35 comprising a one-piece casting having a cylinder 36 closed at one end by a partition wall 37 substantially intermediate the ends of the jack unit 35, and extending longitudinally of the cylinder 36, adjacent the partition 37, is a reservoir 38 and a pump cylinder 39, the reservoir 38 being integrally arranged above the pump cylinder 39; and the jack unit 35 is pivotally connected between the side walls 11 and 12 by spaced ears 40 integral with one end of the reservoir 38, and the ears 40 are provided with apertures for pivotal engagement with a rod 41 fixedly secured by nuts 42 to the side walls 11 and 12, thus permitting the jack unit 35 and its associated parts to be swung upwardly and downwardly between the side walls 11 and 12.

Reciprocally mounted in the cylinder 36 is a ram 43 having a piston 44 at its inner end, and the piston 44 embodies an annular flange 45 integral with the ram 43, short of the inner end thereof, and the flange 45 merges into a reduced integral solid stud 46 exteriorly threaded for the reception of a pilot 47 which clamps an inverted cup-shaped packing member 48 against the shoulder formed by the flange 45 and the reduced stud 46. The pilot 47 has a reduced portion which engages the depending flange 49 of the packing member 48, and the depending flange 49 has its peripheral edge beveled and spaced from the enlarged portion of the pilot 47, forming an annular recess 50 therebetween. The pilot 47 is also provided with annularly spaced ports 51 which communicate with the recess 50, so that when fluid is forced into the cylinder 36, adjacent the piston 44, it will pass through the ports 51 into the recess 50 and force the flange 49 into intimate contact with the cylinder 36.

The cylinder 36 is also provided with a lateral port 52 intersecting a by-pass 53 extending longitudinally along the cylinder 36 communicating at one end with the reservoir 38, and the opposite end terminating at the outer extreme end of the cylinder 36, and the port 52 terminates at the outer surface of the cylinder 36, being closed by a threaded plug 54.

The outer end of the cylinder 36 is internally screw-threaded to receive a correspondingly threaded closure 55 provided with a laterally extending annular shoulder 56 for seating engage-

ment with a packing washer 57 interposed between the shoulder 56 and the outer extremity of the cylinder 36. The end of the ram 43, opposite the piston 44, extends through a centrally disposed aperture 58, formed by an annular depending flange 59 in the closure 55, and the flange 59 is disposed in intimate contact with the ram 43 so as to pilot the ram 43 when it is reciprocated therethrough. Leakage of fluid beyond the flange 59 is prevented by means of a packing member 60 disposed within an internally screw-threaded recess 61 formed in the closure 55, and is held in sealing engagement with the ram 43 by a nut 62 threaded into the closure 55.

15 The outer end of the ram 43 has a flattened portion 63 apertured for the reception of a pin 64 fixedly secured therein by means of a set-screw 65 threaded through the flattened portion 63 into contact with the pin 64, and the opposite 20 ends of the pin 64 are pivotally accommodated by apertures 66 disposed in inwardly extending spaced trunnions 67 integral with the walls 68 and 69 of a one-piece casting 70, disposed between the side walls 11 and 12 of the frame 10.

25 The walls 68 and 69 of the casting 70 are triangular in transverse section and are integrally connected by a plurality of tie members, as indicated at 71, and one apex, as indicated at 72, is pivotally connected to a rod 73 disposed between the apexes 73 of the walls 11 and 12 and secured to the walls 11 and 12 by nuts 74. The other apex, as indicated at 75, of the side walls 68 and 69 has interposed therebetween a saddle support 76, provided at one end 30 with a cylindrical portion 77 bored out for pivotal connection with a pin 78 extending therethrough, and the pin 78 terminates in apertures disposed in the side walls 68 and 69, the pin 78 being rigidly affixed therein by set-screws 79 threaded through the side walls 68 and 69 into contact 35 with the pin 78. Integral with the cylindrical portion 77 and inclined downwardly therefrom is a pair of lever arms 80 each having at its lower end a trunnion 80, apertured for pivotal engagement with bolts 81 each extending through one 40 of the trunnions 80, the heads of the bolts 81 being each secured in correspondingly shaped bores in one end of balancing links 82 and 83, the opposite ends of which are pivotally secured by 45 means of bolts 84 to the side walls 11 and 12 of the frame 10. A saddle 85 is detachably secured to the saddle support 76 by a bolt 86, and is adapted to engage the object to be elevated. The casting 70 thus provided comprises an elevatable 50 member adapted to be swung about the rod 73 between the side walls 11 and 12.

Fluid under pressure is supplied to the cylinder 36 from the reservoir 38 by means of a pump, indicated as an entirety at 90, and comprises the pump cylinder 39 cast integrally with the lower side wall of the reservoir 38, and which communicates at its inner end with a bore 91 opening at the inner end of the cylinder 36, having a valve seat 92 for the accommodation of a ball valve 93 held normally closed by a spring 94 interposed between the ball valve 93 and a removable spider member 95 threaded into the bore 91 at the end opening into the cylinder 36. The bore 91 also communicates with an intersecting vertically extending bore 96 leading to the interior of the reservoir 38, having a valve seat 97 for the accommodation of a ball valve 98, held normally closed by a spring 99 interposed between the ball valve 98 and a removable

5 plug 100 threaded into the outer end of the bore 96 in the lower surface of the casting 10.

To prevent foreign matter contained in the fluid in the reservoir 38 from lodging in the valve seats 92 and 97, I provide a screen 101 elevated 5 with respect to the bottom of the reservoir 38, and secured by means of screws 102 within the reservoir 38 over the reservoir outlet to the bore 91. The upper wall 103 of the reservoir 38 is provided with a removable cover 104, whereby 10 access may be had to the interior of the reservoir 38.

Reciprocally mounted in the pump cylinder 39 is a plunger 105 provided at its inner end with a packing 106 held in position by a screw 107, and the outer end of the plunger 105 extends through a gland nut 108 threaded into the pump cylinder 39, compressing a packing member 109 about the plunger 105 in fluid sealing relation. The outer extremity of the plunger 105 is apertured 20 to pivotally accommodate a pin 110, the opposite ends of which are each pivotally connected to one end of a pair of links 112, the opposite ends of the links 112 being pivotally connected by means of bolts 113, to the extreme end of the 25 furcated portions 114 of a forked handle support 115. The furcated portions 114 are enlarged transversely short of the ends thereof, each being provided in the enlarged portion with a bore 116 for the accommodation of a 30 bushing 117 flanged at its outer end to bear against the surface of the furcated portions 114, and the bushings 117 are each interiorly threaded for the reception of a bolt 118 extending through the elongated section 16 of the side 35 walls 11 and 12, the furcated portions 114 thus being rotatable about the bushings 117, so that oscillatory movement of the handle support 115 and its associated parts causes reciprocatory movement of the pump plunger 105. The stem 40 portion 120 of the handle support 115 is interiorly threaded for the reception of an elongated tubular pump handle 121 terminating in a transverse hand grip 122, whereby the pump handle 121 may be oscillated. 45

The escape of fluid from the cylinder 36 is controlled by means of a needle valve 125 partially disposed in the reservoir 38, and the inner end of the needle valve 125 fits within a bore 126 extending through the partition 37 for 50 establishing communication between the interior of the cylinder 36 and the reservoir 38 when the valve 125 is unseated. The outer end of the valve 125 extends through a boss 127 formed interiorly of the wall of the reservoir 38, and 55 through a packing member 128 and a gland nut 129 provided with an external thread for threaded reception in to the boss 127, and also threaded interiorly for engagement with a correspondingly threaded portion 130 of the needle 60 valve 125 so that when it is desired to allow the ram 43 to enter the cylinder 36 from an extended position, the valve 125 is unscrewed, which moves it axially, thus retracting the valve 125 from engagement with the bore 126 and 65 permitting the fluid confined under pressure within the cylinder 36 to escape back to the reservoir 38.

In order to rotate the needle valve 125 at a point remote therefrom, I provide a universal 70 connection, as indicated at 131, one link 132 having one end secured to the extreme outer end of the needle valve 125, and the other end to a link 133 forming part of another universal connection indicated at 134, and which is con- 75

5 nected to a link 135 having threaded thereon a collar 136 for adjusting the length of the link 135 threaded into a valve rod 137 guided at its lower end by a nut 138 threaded into the lower end of the pump handle 121, and the valve rod 137 extends through the pump handle 121 beyond the hand grip 122, terminating in a knob 140 adjacent the hand grip 122. By rotating the knob 140, the valve rod 137 is rotated, which 10 in turn operates the needle valve 125.

Disposed about the pump handle 121 adjacent the upper end of the handle support 115 is a bracket 141 extending laterally therefrom in spaced relation with respect to the arcuate segments 17, and the bracket 141 is detachably secured to the pump handle 121 by means of a bolt and nut 142. The opposite ends of the bracket 141 are provided with an aperture 139 for the reception of locking pins 143 adapted to be inserted in the apertures 19 of the arcuate segment 17, and the opposite ends of the pins 143 are rigidly secured in a bracket 144 fixedly attached to the lower end of a sleeve 145 slidably disposed about the pump handle 121. And the pins 143 are normally maintained in a retracted position with respect to the holes 19 by means of a spring 146 interposed between the brackets 141 and 144 about the locking pins 143. The upper end of the sleeve 145 is loosely embraced by a collar 147 integral with a locking cam 148 having an inclined surface 149 normally in juxtaposition with a like contoured surface 150 of a cam bracket 151 fixedly secured to the pump handle 121, and the locking cam 148 is provided with a handle 152 to rotate the cam 148 with respect to the cam bracket 151 and the sleeve 145, causing downward movement of the sleeve 145 and the bracket 144, placing the locking pins 143 in contact with the flanges 18, and the pins 143 are brought into coincidence with any of the apertures 19 by movement of the pump handle 121, thus the pump handle 121 and its associated parts can be rigidly locked in a plurality of operative positions.

45 In operation, assuming the saddle 85 to be in lowered position, fluid is forced into the cylinder 36 by vertical oscillation of the handle 121, the oscillatory movements being transmitted through the furcated portions 114 of the handle support 115, and thence to the links 112 connected to the pump plunger 105, which moves outwardly when the handle 121 is moved upwardly, and unseats the ball valve 98, permitting fluid to pass from the reservoir 38 into the bore 91, and upon downward movement of the handle 121 the pump plunger 105 moves inwardly of the cylinder 39, forcing the fluid in the bore 91 to seat the ball valve 98 and to unseat the ball valve 93, which permits the entrance of fluid under 60 pressure into the cylinder 36 adjacent the piston 44. Such fluid entering the cylinder 36 forces the ram 43 outwardly of the cylinder 36, and the ram 43 rotates the elevatable member 70 about the rod 73, effecting elevation of the saddle 65 85, which is maintained in a horizontal position during elevation to any position by the balancing links 82 and 83, pivoted to the saddle 85 and the side walls 11 and 12 of the frame 10. The jack unit 35, which includes the cylinder 70 36, reservoir 38 and pump cylinder 39, also oscillates about the rod 41 as the elevatable member 70 is rotated; the jack unit 35 being movable in an arcuate line to allow arcuate movement of the elevatable member 70. When the 75 saddle 85 has been raised to the desired height,

it is locked in such elevated position by rotating the locking cam 148, which causes engagement of the locking pins 143 with the cooperating apertures 19. When the ram 43 has reached the limit of its outward movement, the piston 44 uncovers the port 52 and fluid may escape through the by-pass 53 to the reservoir 38, thus automatically arresting outward movement of the ram 43 and also upward movement of the saddle 85. The needle valve 125 is moved to open position by rotating the knob 140, which in turn rotates the universal connections 131 and 134 which axially displace the valve 125, permitting return of the fluid from within the cylinder 36 adjacent the piston 44 into the reservoir 38 and consequent lowering of the saddle 85. Oscillation of the handle 121 does not affect the operation of the needle valve 125 because of the universal connections 131 and 134, and the needle valve 125 may be operated when the handle 121 is in locked position.

It will be apparent that I have provided a jack wherein the parts necessary to operate the jack are close to each other, the release valve 125 having its cooperating parts extending through the tubular pump handle 121, and its operative knob 140 adjacent the hand grip 122, and the locking cam 148 located on the pump handle 121.

It will be apparent to those skilled in the art that the embodiment herein disclosed accomplishes at least the principal objects of the invention, and includes advantages other than those herein disclosed, and that various changes and modifications may be made without departing from the spirit of the invention; and accordingly the embodiment herein disclosed is illustrative only and the invention is not limited thereto.

I claim:

1 claim.

1. A hydraulic jack, comprising: an elongated frame having side members of appreciable height and cross members extending between the top and bottom edges of said side members and integrally formed therewith, said frame being made up from an integral casting of malleable metal, and said side members having integral spaced extensions projecting beyond the rearmost cross member, and each of said extensions provided with an angular flange having spaced recesses therein, and the front and rear portions of said frame carrying rollers; a lever having integrally formed side and cross members and carrying a supporting member adjacent one end, and pivotally carried by said frame adjacent its opposite end; a hydraulic unit including a pump cylinder and reservoir vertically aligned with said pump cylinder, and a ram cylinder longitudinally aligned with respect to said reservoir and pump cylinder, and a ram in said ram cylinder having its outer end pivotally connected to said lever at a point below the point of connection of said lever with said frame, and said hydraulic unit being pivotally connected to said frame at a higher level than the pivotal connection of said ram; valve means effective to withdraw fluid from said reservoir and admit the same to said ram cylinder when said pump is operated; a hollow operating member having a transverse hand-piece, said member being pivoted to said frame, having a crank, and linkage connecting said crank to the piston of said pump for operating the latter, said member carrying spring pressed pins adapted to bear on said frame flanges and selectively engageable with the recesses in said flanges; a rotatable relief valve for said ram.

cylinder; and a rod extending through said operating member, and connected with said hand-piece, said rod having a universal connection with said rotatable valve.

5. A hydraulic jack, comprising: an elongated frame having side members of appreciable height and cross members extending between the top and bottom edges of said side members and integrally formed therewith, said frame being made 10 up from an integral casting of malleable metal, and said side members having integral spaced extensions projecting beyond the rearmost cross member, and at least one of said extensions provided with an angular flange having spaced recesses therein; a lever having a supporting platform adjacent one end, and pivotally carried by said frame adjacent its opposite end; a hydraulic unit carried by said frame, including a pump cylinder, a reservoir, a ram cylinder, and a ram 15 having its outer end pivotally connected to said lever at a point to one side of the point of connection of said lever with said frame; valve means effective to withdraw fluid from said reservoir and admit the same to said ram cylinder when 20 said pump is operated; and an operating member pivoted to said frame, having means connecting said operating member to the piston of said pump for operating the same, said operating member carrying a spring pressed pin adapted 25 to bear on said flange and selectively engageable with said recesses in said flange.

3. A hydraulic jack, comprising: an elongated frame having side members of appreciable height and cross members extending between the top and 35 bottom edges of said side members and integrally formed therewith, said frame being made up from an integral casting; a lever having a supporting platform adjacent one end, and pivotally carried by said frame adjacent its opposite end; a hydraulic unit, comprising a casting, including 40 a pump cylinder, a reservoir, and a ram cylinder, and having a ram in said ram cylinder, with its outer end pivotally connected to said lever at a point to one side of the point of connection of said lever with said frame, said casting being pivotally connected to said frame at a 45 higher level than the pivotal connection of said ram; valve means carried by said casting, and effective to withdraw fluid from said reservoir, and to admit the same to said ram cylinder when 50 said pump is operated; and an operating member pivoted to said frame, having a crank, and linkage connecting said crank to the piston of said pump for operating the same.

55. 4. A hydraulic jack, comprising: an elongated frame having side members of appreciable height and cross members extending between the top and bottom edges of said side members and integrally formed therewith, said frame being made 60 up from an integral casting; a lever having a supporting platform adjacent one end, and pivotally carried by said frame adjacent its opposite end; a hydraulic unit including a pump cylinder, a reservoir, a ram cylinder, and a ram in said 65 ram cylinder having its outer end pivotally connected to said lever at a point to one side of the point of connection of said lever with said frame, and said hydraulic unit being pivotally connected to said frame; valve means effective to withdraw 70 fluid from said reservoir and admit the same to said ram cylinder when said pump is operated; a hollow operating member having a hand-piece, said member being pivoted to said frame, and having a crank, and linkage connecting said 75 crank to the piston of said pump for operating

the same; a relief valve for said ram cylinder; and valve operating means extending through said operating member and connected with said hand-piece, said means having a universal connection with said relief valve.

5. A hydraulic jack, comprising: an elongated frame; a lever having a supporting platform adjacent one end, and pivotally carried by said frame adjacent its opposite end; a hydraulic unit including a pump cylinder, a reservoir, and a 10 ram cylinder, and a ram in said ram cylinder having its outer end pivotally connected to said lever at a point to one side of the point of connection of said lever with said frame, and said hydraulic unit being pivotally connected to said frame; 15 valve means effective to withdraw fluid from said reservoir and admit the same to said ram cylinder when said pump is operated; a hollow operating member having a hand-piece, said operating member being pivoted to said frame, having means connecting said operating member to the piston of said pump for operating the same; a rotatable relief valve for said ram cylinder; and operating means extending along said operating member, and connected with said hand-piece, 20 said means having a universal connection with said relief valve.

6. A hydraulic jack, comprising: an elongated frame; lever means having a supporting platform adjacent one end, and having a pivotal connection with said frame adjacent its opposite end; hydraulic unit means, including a pump cylinder and piston, a reservoir, and ram cylinder, and ram means in said ram cylinder, one of said means being pivotally connected to said frame 35 and the other of said means being pivotally connected to said lever means at one side of its pivotal connection with said frame to effect operating movements of said lever means when said ram means is operated; said pump cylinder and 40 said reservoir, being disposed side by side integral with, and substantially longitudinally in line with, said ram cylinder; and means for operating said pump to withdraw fluid from said reservoir and to introduce said fluid into said ram cylinder to 45 operate said ram means.

7. A hydraulic jack, comprising: an elongated frame; lever means having a supporting platform adjacent one end, and having a pivotal connection with said frame adjacent its opposite 50 end; hydraulic unit means, including a pump cylinder and piston, a reservoir, and ram cylinder, and ram means in said ram cylinder, one of said means being pivotally connected to said frame and the other of said means being pivotally connected to said lever means at one side of its pivotal connection with said frame to effect operating movements of said lever means when said ram means is operated; said pump cylinder and said 55 reservoir being disposed side by side and substantially longitudinally in line with said ram cylinder; valve means controlling inlet of fluid to said ram cylinder; a screen for screening the fluid entering said valve means; said reservoir having a filling opening, normally closed by a 60 detachable closure, said opening being laterally in line with said screen to give access to said screen as well as to the interior of said reservoir.

8. A hydraulic jack, comprising: an elongated frame; lever means having a supporting platform adjacent one end, and having a pivotal connection with said frame adjacent its opposite end; hydraulic unit means, including a pump, a reservoir, and a ram cylinder, and ram means in said ram cylinder, one of said means being piv- 70

totally connected to said frame and the other of said means being pivotally connected to said lever means at one side of its pivotal connection with said frame to effect operating movements of said lever means when said ram means is operated; said pump and said reservoir being disposed side by side integral with, and substantially longitudinally in line with said ram cylinder, said ram cylinder having a channel communicating with 5 said reservoir, extending longitudinally therealong, and having a laterally disposed relief duct communicating with said channel and with the interior of said ram cylinder; and means effective to withdraw fluid from said reservoir and to 10 introduce the same into said ram cylinder when said pump is operated to operate said ram.

9. A hydraulic jack, comprising: an elongated frame; lever means having a supporting platform adjacent one end, and having a pivotal connection with said frame adjacent its opposite end; hydraulic unit means, including a pump, a reservoir, and ram cylinder, and ram means in said ram cylinder, one of said means being pivotally connected to said frame and the other of said means being pivotally connected to said lever means at one side of its pivotal connection with said frame to effect operating movements of said lever means when said ram means is operated; said pump and said reservoir being disposed side 20 by side integral with and substantially longitudinally in line with said ram cylinder; valve means for effecting withdrawal of fluid from said reservoir and introduction of the same into said ram cylinder when said pump is operated; said ram cylinder having a relief port communicating with said reservoir; and a needle valve extending through said reservoir for controlling said port, said needle valve being accessible for operation at the rear of said reservoir.

40 10. A hydraulic jack, comprising: an elongated frame; lever means having a supporting platform adjacent one end, and having a pivotal connection with said frame adjacent its opposite end; hydraulic unit means, including a pump, a reser-

voir, and ram cylinder, and ram means in said ram cylinder, one of said means being pivotally connected to said frame and the other of said means being pivotally connected to said lever means at one side of its pivotal connection with said frame to effect operating movements of said lever means when said ram means is operated; said pump and said reservoir being disposed side by side integral with, and substantially longitudinally in line with said ram cylinder; valve 10 means for effecting withdrawal of fluid from said reservoir and introduction of the same into said ram cylinder when said pump is operated; said ram cylinder having a relief port communicating with said reservoir; a needle valve extending 15 through said reservoir for controlling said port, said needle valve being accessible for operation at the rear of said reservoir; and means for operating said pump, said means carrying mechanism by which the position of said needle valve may be 20 controlled.

11. A hydraulic jack, comprising: an elongated frame; lever means having a supporting platform adjacent one end, and having a pivotal connection with said frame adjacent its opposite end; hydraulic unit means, including a pump, having a pump cylinder and piston, a reservoir, and ram cylinder, and ram means in said ram cylinder, one of said means being pivotally connected to said frame and the other of said means being 25 pivotally connected to said lever means at one side of its pivotal connection with said frame, to effect operating movements of said lever means when said ram means is operated; said pump cylinder, and said reservoir, and said ram cylinder, comprising a single casting, recessed to dispose the pump cylinder longitudinally in line with one side of the ram cylinder, and to form the reservoir longitudinally in line with an opposed side of said ram cylinder; and means for 30 operating said pump to withdraw fluid from said reservoir, and to introduce said fluid to said ram cylinder to operate said ram means.

HOMER R. ROSENBERRY.
